(57) **CLAIM**

The ornamental design for a folding lock back knife with a thumb latch blade retention wire, as shown and described.

DESCRIPTION

FIG. 1 is a front perspective view of a folding lock back knife with a thumb latch blade retention wire, showing my new design in an extended configuration;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a bottom plan view of FIG. 1;

FIG. 9 is a front perspective view thereof, illustrated in a retracted configuration;

FIG. 10 is a rear perspective view of FIG. 8;

FIG. 11 is a front elevational view of FIG. 8;

FIG. 12 is a rear elevational view of FIG. 8;

FIG. 13 is a left-side elevational view of FIG. 8;

FIG. 14 is a right-side elevational view of FIG. 8;

FIG. 15 is a top plan view of FIG. 8; and,

FIG. 16 is a bottom plan view of FIG. 8.

The broken lines in the figures depict portions of the folding lock back knife with a thumb latch blade retention wire that form no part of the claimed design.

1 Claim, 8 Drawing Sheets
